UNITED STATES PATENT OFFICE.

THEODORA ZAKRZEWSKI, OF PHILADELPHIA, PENNSYLVANIA.

DESIGN FOR A SYMBOL.

42,181.

Specification for Design.

Patented Feb. 13, 1912.

Application filed May 20, 1910. Serial No. 562,559. Term of patent 3½ years.

To all whom it may concern:

Be it known that I, THEODORA ZAKRZEWSKI, a citizen of the United States, residing at Philadelphia, in the county of Philadelphia and State of Pennsylvania, (whose post-office address is 2034 Tioga street,) have invented a new, original, and ornamental Design for Symbols, of which the following is a specification, reference being had to the accompanying drawing, forming part thereof.

The figure is a plan view showing my new design.

The design is included on a circular background with a marginal band for inscriptions. The central portion thereof is provided with a representation of a four-leaf-clover, on the leaves of which appear inscriptions and the figures. The figures shown in this design are: a figure, mouth covered; a figure, hand held; a figure, foot held; a figure, arm raised, or extended.

I claim—

The ornamental design for a symbol as shown and described.

THEODORA ZAKRZEWSKI.
